UNITED STATES PATENT OFFICE.

MERLE R. MEACHAM, OF ELIZABETH, NEW JERSEY, ASSIGNOR TO STANDARD OIL DEVELOPMENT COMPANY, A CORPORATION OF DELAWARE.

DISTILLATION OF HYDROCARBONS.

Application filed June 25, 1923. Serial No. 647,517.

This invention relates to the art of distilling hydrocarbons and will be fully understood from the following description taken in connection with the accompanying drawing in which—

Fig. 1 is a longitudinal section of apparatus embodying the features of the invention, and

Fig. 2 is a section taken on the line II—
10 of Fig. 1.

In the customary procedure of distilling hydrocarbons with the use of bottom steam, i. e. steam injected along the lower part of the still, customarily by a plurality of perforated pipes, the only contact between the steam and oil is that resulting as the bubbles of steam ascend through the body of oil.

I have found that the contact between steam and oil as secured in this manner of operating is too incomplete to allow of the proper utilization of the steam with respect to its distilling and vapor-carrying capacity. Correspondingly the efficiency of the customarily designed apparatus is quite low as 25 compared with what a proper utilization of the steam should accomplish.

In accordance with the present invention I have provided the application of steam in such manner as to secure the usual contact 30 as the bubbles ascend through the liquid and additionally secure further and repeated intermingling and contact of the rising steam and the hot liquid undergoing distillation, this being accomplished in such manner as 35 to allow of an extended distillation effect and the taking up of hydrocarbon vapors to a large extent of the capacity of the steam.

Referring particularly to the drawings, the reference character 1 designates a still 40 which may be of the usual shell type, and projecting into the top and on down to header connections are steam supply pipes 2. From the header, distributing pipes 3 extend longitudinally along the floor of the 45 still, these pipes having preferably perforations directed toward the bottom of the still. A dome 4 arranged toward one end of the still has the usual vapor-offtake pipe 5, and arranged preferably beneath the dome 50 is a circulating device 6, taking the form for example of an open-ended tube, the lower end being near the bottom of the still and the upper end extending just into the dome. Under the tube 6 and arranged to discharge 55 into it is a steam jet pipe 7. Above the

tube 6 is a hood deflector 8, and in relation to this so as to divert liquid downwardly are deflector plates 9 and 10, these being arranged in suitably overlapping and spaced positions. A trough, which may be in two sections designated 11 and 12, is positioned under the deflector plates so as to catch liquid which is discharged from the top of tube 6, and the construction of this trough is such as to carry the liquid along and uniformly distribute it over the sides of the trough; for example, in the form shown the side walls of the trough are shaped with over-flow feed edges. Beneath the trough are spaced a plurality of plates or baffles 13, 60 these extending longitudinally of the still and being positioned with respect to each other so as to receive in progressive succession the liquid overflowing from the sides of the trough and cascade it down by a plurality of stages through the upper portion of the vapor space of the still. 65

With the still operating, the oil being subjected to heat and the thorough agitation produced by the steam admitted to the inlet 80 pipes 3, vapors are carried up and the bubbles of steam traversing the oil escape at its upper surface and proceed toward the dome. At the same time the steam supplied through the jet pipe 7 raises quantities of 85 the hot oil from the lower portion of the still, splashing it out over the deflector plates 9 and 10 from whence it runs down into the trough 11 and 12, and flowing therefrom it distributes in thin cascades onto the 90 upper baffle plates 13, flowing down from plate to plate in succession toward the body of oil. In cascading down through the upper portion of the still in this manner the hot oil is brought into very effective contact with the ascending steam. 95

The precise form and arrangement of structure for affording cascading contact of the hot liquid with the rising steam may be varied, the arrangement however retaining the general feature of a plurality of baffle plates or the like to afford a fall of the oil through the upper portion of the still in finely divided or film-flow condition. For instance, instead of a trough and solid plates as baffles, I also contemplate the provision of perforated plates or woven wire fabric sheets suitably spaced so as to break up and further distribute the oil flowing down from the upper part of the still. It 100 105 110

will be seen that in essence the invention contemplates the carrying of hot oil from the lower portion of the still and distributing such oil through the rising current of steam in such manner as to secure a widely spread and repeated contact of oil with steam, and while I have shown a form of construction illustrative of the invention and comprising certain specific agencies, it will be understood that changes may be made within the spirit and scope of the invention.

What I claim is:

1. Apparatus of the character described which comprises a still, multi-perforated steam inlet pipes along the bottom of the still, an open-ended circulating tube projecting upwardly into the still from a point near the bottom, a steam jet beneath said circulating tube, deflector plates and a trough 20 near the upper end of the circulating tube for receiving liquid discharged from the tube, said trough extending longitudinally of the still and having its side walls shaped with liquid distributing edges, and a plurality of spaced liquid distributing baffles under the trough.

2. Apparatus of the character described which comprises a still, multi-perforated steam inlet pipes along the bottom of the still, an open-ended circulating tube projecting upwardly into the still from a point 30 near the bottom, a trough for receiving liquid discharged from the tube, said trough extending longitudinally of the still and having its side walls shaped with liquid distributing edges, and a plurality of spaced liquid distributing baffles under the trough.

3. Apparatus of the character described which comprises a still, multi-perforated 40 steam inlet pipes along the bottom of the still, an open-ended circulating tube projec-

ting upwardly into the still from a point near the bottom, means for injecting steam into the lower end of said circulating tube, means for receiving and temporarily retaining liquid discharged from said tube, and a plurality of spaced baffles under said receiving means and upon which said liquid overflows.

4. Apparatus of the character described 50 which comprises a still adapted for the steam treatment of hydrocarbon oils, multi-perforated steam inlet pipes along the bottom of the still, means for raising liquid hydrocarbons to the upper part of the still, 55 and means for distributing such liquid in cascade in a plurality of stages through the upper portion of the still and in contact with steam from said inlet pipes.

5. The improvement in the art of distilling 60 hydrocarbon oils, which comprises heating a body of oil, bubbling steam therethrough, elevating a portion of the oil by means of separately injected steam, and cascading such elevated portion through a plurality of 65 stages in contact with steam and accompanying oil vapors rising from the upper surface of the oil in the still.

6. An apparatus of the character described, which comprises a still containing 70 a liquid oil, means having a large number of orifices for introducing steam into a lower part of the still in effective distilling contact with the liquid therein, means for raising liquid from the lower to the upper 75 part of the still, and means arranged in a plurality of stages for cascading liquid raised from the lower part of the still so as to afford contact with vapors in the upper part of the still.

MERLE R. MEACHAM.
